UNITED STATES PATENT OFFICE.

RONALD A. McCANN, OF NEW BRUNSWICK, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,204,998.

Specification of Letters Patent.

Patented Nov. 14, 1916.

Application filed February 7, 1914. Serial No. 817,105.

To all whom it may concern:

Be it known that I, RONALD A. McCANN, a citizen of the United States, residing at New Brunswick, in the county of Middlesex and State of New Jersey, have invented certain new and useful Improvements in Railway Signaling, of which the following is a specification.

My invention relates to railway signaling, and particularly to signaling for stretches of single track over which traffic moves in both directions, such, for example, as stretches of single track between passing sidings.

I will describe several forms of signaling systems embodying my invention, and will then point out the novel features thereof in claims.

In the accompanying drawings, Figure 1 is a diagrammatic view showing a stretch of track having applied thereto one form of signaling system embodying my invention, the signals being of the two-position type indicating clear and danger, and the intermediate signals governing traffic in opposite directions being oppositely located. Fig. 2 is a view similar to Fig. 1 but showing one arrangement of control when the signals governing traffic in opposite directions are not oppositely located. Fig. 3 is a view similar to Fig. 2 but showing another arrangement of control when the signals governing traffic in opposite directions are not oppositely located. Fig. 4 is a view similar to Fig. 1, but showing signals of the three-position type, indicating danger, caution and clear.

Similar reference characters refer to similar parts in each of the views.

Referring first to Fig. 1, A—B is a stretch of single track between two passing sidings E and F, over which stretch traffic moves in both directions. Traffic through this stretch from east to west is governed by signals S', S² and S³ located at intervals through the stretch, and traffic through the stretch from west to east is governed by other signals S², S⁴ and S⁵, located also at intervals through the stretch.

The stretch A—B is divided by insulated joints 3 into several successive sections A—C, C—D and D—B, and in this view a pair of opposing signals is located near each junction of adjacent sections. Each section is provided with one or more track circuits including track relays for the control of the signals. As here shown each section is di-

vided by insulated joints 3 into two sub-sections, and each sub-section is provided with a separate track circuit. For example, section A—C is divided into two sub-sections A—H and H—C. Each track circuit comprises the rails of the sub-section, a battery b, and a track relay, the latter being designated by the reference character T with the same exponent as that of the adjacent signal which governs traffic through the corresponding sub-section.

For each signal I provide a signal relay for the control thereof, which relays are designated in the drawing by the reference character R with an exponent corresponding to the exponent of the signal which the relay controls. Each signal is provided with a circuit which is controlled by the corresponding signal relay. For example, the circuit for clearing signal S³ is from battery P³ through wires 11, 12, 13, contact 14 of relay R³, wire 15, mechanism of signal S³, wire 16, contact 17 of relay R³, wires 18 and 19 to battery P³. I will assume that each signal comprises an electric motor for moving the semaphore toward clear position against the action of gravity, and that the motor is connected with the semaphore to be driven thereby while the latter is returning toward danger position; if then the circuit of the motor is closed during the latter movement the motor acts as a brake to retard the movement of the semaphore. The circuit for signal S³ by which this is accomplished is from the signal mechanism through wire 16, back point of contact 14 of relay R³, wire 15 to the signal mechanism. This circuit is closed when relay R³ opens. The driving and braking circuits for each of the other signals are similar to those just traced for signal S³.

Extending through the stretch A—B are two signal relay circuits, one of which normally includes in multiple the relays controlling the eastbound signals and the other of which normally includes in multiple the relays controlling the westbound signals, which circuits are controlled by the several track relays. Each of these circuits includes a series of line conductors and a common return conductor O, and each circuit includes a main source of current M' or M². Considering, for example, the signal relays for the eastbound signals, the circuit for relay R⁶ is from main battery M', through wire 21, contact 22 of relay T', wire 23, contact 24 of

- track relay T^6 , wires 25 and 341, relay R^6 , wires 27, 28 and 29, common return wire O to battery M' . The branch for signal relay R^4 leaves the circuit just traced at wire 25 and then passes through wire 26, back point of contact 30 of an auxiliary relay X^6 (hereinafter explained), wire 31, back point of contact 32 of another auxiliary relay X^3 , wire 33, contact 34 of track relay T^3 , wire 35, contact 36 of track relay T^4 , wires 37 and 38, relay R^4 , wires 39, 40, 41, to return wire O , to battery M' . Similarly, the branch for relay R^2 leaves the circuit just traced at wire 37 and is similar to the branch for relay R^4 .
- 15 The circuit for the signal relays for the westbound signals is similar to that just explained for the eastbound signals. It will be seen from the foregoing that the main battery for each of these signal relay circuits is located adjacent the end of the stretch at which traffic governed by the corresponding signals leaves the stretch.
- 20 Located adjacent each intermediate signal is an auxiliary source of current, which sources are designated by the reference character P with the same exponent as that of the corresponding signal. For each intermediate signal I also provide an auxiliary relay, which latter are designated by the reference character X with the same exponent as that of the corresponding signal. As noted hereinbefore, the signal relay circuits are controlled by back contacts of these relays.
- 25 Each auxiliary relay is adapted when closed to open at that point the signal relay circuit of which the relay for the corresponding signal forms a part, and to connect the corresponding auxiliary source of current with the portion of such circuit extending in the rear of the point of opening. For example, auxiliary relay X^3 , when closed, reverses contact 42 included therein, and this contact opens the normal circuit 30 for signal relay R' and connects this relay with auxiliary battery P^3 . Similarly, auxiliary relay X^5 , when closed, disconnects relays R^3 and R' from main battery M^2 and connects them with auxiliary battery P^5 .
- 35 Each auxiliary relay is provided with a pick-up circuit and a holding circuit, the pick-up circuits, in the form of my invention shown herein, being controlled by signal operated contacts. For this purpose, 40 each signal is provided with a contact device comprising a finger 43 which engages a fixed contact plate 44 or 45 according as the signal is in the clear or the danger position.
- 45 The pick-up circuit for auxiliary relay X^3 is from battery P^3 through wires 11, 46 and 47, contact 48 of relay X^6 , wire 49, contact 45-43 operated by signal S^6 , wire 50, contact 43-44 operated by signal S^3 , wires 51 and 52, relay X^3 , wires 53, 18 and 19 to

battery P^3 . It will be seen that this circuit can be closed only when signal S^3 is in the clear position and signal S^6 in the danger position and also only when auxiliary relay X^6 is deenergized. The holding circuit for auxiliary relay X^3 is from battery P^3 through wires 11, 12 and 54, back point of contact 55 of relay R^3 , wire 56, contact 57 of relay X^3 , wires 58 and 52, relay X^3 , wires 53, 18 and 19 to battery P^3 . It will be seen that this circuit is closed only when relay X^3 is energized and relay R^3 deenergized. The circuits for each of the other auxiliary relays are similar to those for relay X^3 .

50 The operation of the apparatus shown in Fig. 1, during the passage of a westbound car or train through the stretch $A-B$, is as follows: As the train enters sub-section $B-N$, it opens track relay T' , thereby opening at contact 59 the circuit for signal relay R' , so that signal S' changes to danger position. The opening of contact 22 of relay T' opens the multiple circuit including signal relays R^6 , R^4 and R^2 , so that all of these relays become deenergized, thereby causing signals S^6 , S^4 and S^2 to change to danger position. It will be seen, therefore, that as soon as a car or train enters the sub-section $B-N$ all signals governing traffic from west to east change to danger position. The movement of signals S^6 and S^4 to danger closes the pick-up circuits of auxiliary relays X^3 and X^5 so that these relays then close. The closing of relay X^3 opens at that point the multiple circuit for the westbound signal relays and connects auxiliary battery P^3 with the portion of this circuit extending to the rear, but relay R' remains deenergized because track relay T' is open. Similarly relay X^5 opens the signal relay circuit at that point and connects the portion extending to the rear with auxiliary battery P^5 , so that relay R^3 is now energized from the latter source. Relay R^5 continues to be energized from main battery M^2 . As the train enters sub-section $N-D$, it opens track relay T^6 , but this has no effect on the signals, because the contacts of this relay control the same circuits as the contacts of track relay T' . As the train enters sub-section $D-Q$, it opens track relay T^3 , thereby opening at contact 60 of this relay the circuit for signal relay R^3 , so that signal S^3 then changes to danger position. Inasmuch as auxiliary relay X^3 was already closed, its holding circuit is now closed at contact 55 of relay R^3 . The opening of contact 34 of track relay T^3 has no effect on the signals, because relays R^4 and R^2 , which are controlled by this contact, are already open. When the rear of the train leaves sub-section $N-D$ it allows track relay T^6 to close thereby energizing signal relay R' from auxiliary battery P^3 , so that

signal S' then moves to clear position, thereby permitting a following westbound car or train to enter the stretch A—B. The closing of track relay T^6 also closes the circuit for relay R^6 , so that signal S^6 then returns to clear position. As the train passes from sub-section D—Q into sub-section Q—C, it opens track relay T^4 and allows track relay T^3 to close, but inasmuch as these relays control the same circuits, the change has no effect on the signals. As the train passes into sub-section C—H, it opens track relay T^5 , thereby opening signal relay R^5 , so that signal S^5 changes to danger. The closing of track relay T^4 closes the circuit for signal relay R^3 from auxiliary battery P^5 , so that signal S^3 then moves to clear position. The closing of relay R^3 opens the holding circuit of relay X^3 so that the latter opens, transferring relay R' from battery P^3 to battery P^5 . As the train leaves the stretch, relay R^6 closes, thereby changing signal S^6 to clear and restoring the parts to the positions shown.

The operation of the apparatus during the passage of an eastbound car or train through the stretch is similar to that just explained for the passage of a westbound car or train.

Referring now to Fig. 2, the system here shown is similar to that shown in Fig. 1, except that the two pairs of intermediate signals S^4 , S^5 , and S^6 , S^3 are staggered instead of being oppositely located. The circuits in Fig. 2 are the same as those in Fig. 1 except the control circuits for the auxiliary relays X . The pick-up circuit for relay X^3 is from battery P^6 through wires 11 and 74, contact 67 of relay X^6 , wire 68, contact 45—43 of signal S^6 , wire 69, contact 43—44 of signal S^3 , wire 70, relay X^3 , wires 71, 72, 73 to battery P^6 . The holding circuit for this relay is from battery P^3 through wires 11, 75 and 76, contact 77 of relay R^3 , contact 78 of relay X^3 , wire 79, relay X^3 , and wire 71 to battery P^3 . The circuits for the other auxiliary relays are similar to those just traced for relay X^3 .

The operation of the system shown in Fig. 2 will be obvious from the foregoing explanation of Fig. 1.

Referring now to Fig. 3, the system here shown is similar to that shown in Fig. 2, except as to the control of the auxiliary relays X . In Fig. 3, I provide an additional relay for each intermediate signal which relay is designated by the reference character Y with the same exponent as that of the corresponding signal. Relays Y^3 and Y^5 are connected in multiple in the circuit of the signal relays for the eastbound signals, and the multiple circuit is carried through front contacts of these relays. Relays Y^4 and Y^6 are similarly connected in the circuit for the signal relays of the westbound signals.

These relays are used to control the pick-up circuits for the auxiliary relays X , and they take the place of signal-operated contacts 43—45 in Fig. 1. The pick-up circuit for auxiliary relay X^3 is from battery P^3 through wires 11 and 80, contact 81 of relay Y^3 , wire 82, contact 43—44, wire 83, relay X^3 , wires 84 and 85 to battery P^3 . The holding circuit for this relay is the same as in Fig. 1. As a train moving west enters section B—D' it causes signal S' to change to danger, and also opens the circuit including the signal relays for the eastbound signals and the additional relays Y^3 and Y^5 . Contacts 81 of these latter relays close the pick-up circuits for auxiliary relays X^5 and X^3 . Then as the train proceeds into section D'—D it opens relay R^3 , thereby closing the holding circuit for relay X^3 . Signal S' then clears, and relay Y^3 closes. The operation of the system during the passage of the train through the remainder of the stretch will now be apparent.

When the arrangement of control shown in Fig. 3 is employed, the relays X are preferably slow-acting, for the following reason: When a light locomotive moving west passes from section N—D' into section D'—D, if track relay T^3 closes before track relay T^6 opens, the pick-up circuit for relay X^3 would be opened before the holding circuit is closed, and if this relay were not slow-acting it might sometimes fail to remain closed under these circumstances. Similar remarks apply to the other auxiliary relays X .

Referring now to Fig. 4, the system here shown is the same as that shown in Fig. 1, except that each signal is of the three-position type, that is, adapted to indicate danger, caution and clear. The signal relays R are in this case of a polarized type for controlling the three positions of the signals. The circuit for moving signal S^3 from danger to caution is from battery P^3 through wires 11, 12 and 13, contact 14 of relay R^3 , wire 15, mechanism of signal S^3 , wire 16, contact 17 of relay R^3 , wires 18 and 19 to battery P^3 . The circuit for moving this signal from the caution to the clear position is the same as that just traced up to and including contact 14, then through wire 61, polarized contact 62 of relay R^3 , wire 63, mechanism of signal S^3 , then to battery P^3 as before. The signal is provided with a braking circuit as in Fig. 1. The circuits for the other signals are similar to those just traced for signal S^3 .

Inasmuch as the signal relays R are polarized, pole-changers are provided for reversibly energizing these relays, the pole-changers being operated as usual by the signals. Each pole-changer is designated by the reference character G with the same exponent as that of the signal which operates

it. Signal relay R^5 is at times controlled by a pole-changer G^7 operated by a signal S^7 which governs traffic into the next adjacent stretch to the west, and this signal is controlled by signal relay R^7 which is in turn controlled by a line wire 64 which corresponds to the line wire 64 shown at the right-hand end of stretch A—B. Similarly, signal relay R^6 is at times controlled by a pole-changer G^8 operated by a signal S^8 which latter is controlled by a signal relay R^8 controlled by a line wire 65, which corresponds to line wire 65 shown at the left-hand end of the stretch. Signals S^3 and S^4 each operate an additional contact 66 for a purpose hereinafter explained.

The operation of the system shown in Fig. 4 during the passage of a westbound train through the stretch A—B is as follows: As the train enters sub-section B—N it opens track relay T' , thereby opening the circuit for signal relay R' so that signal S' changes to danger. Track relay T' also opens the multiple circuit which includes the signal relays for the eastbound signals, so that all of these signals also change to danger, thereby closing the pick-up circuits for auxiliary relays X^3 and X^5 as in Fig. 1. Relay X^5 transfers signal relay R^3 to battery P^5 , but pole-changer G^5 is in such position that signal S^3 continues to indicate clear. As the train proceeds into sub-section N—D the opening of track relay T^6 and the closing of track relay T' do not affect the signals for the stretch A—B because so far as these signals are concerned these relays control the same circuits. As the train enters sub-section D—Q and leaves sub-section N—D, the opening of track relay T^3 opens relay R^3 thereby causing signal S^3 to change to danger. The opening of relay R^3 also closes at the back point of contact 55 the holding circuit of relay X^3 . Signal relay R' is now energized from battery P^3 , but pole-changer G^3 is reversed so that signal S' moves only to caution position. Relay R^6 is now energized and pole-changer G^8 is in such position that signal S^6 moves to clear position. As the train passes into sub-section Q—C it causes no change in the signals and circuits. As it enters sub-section C—H, the opening of track relay T^6 opens signal relay R^5 so signal S^5 changes to danger. Relay X^5 remains closed, so the closing of track relay T^4 closes the circuit for relay R^3 from battery P^6 , but pole-changer G^6 is now reversed so that relay R^3 is energized in such direction that its polar contacts are reversed and signal S^3 therefore moves only to the caution position. While relay R^3 is picking up, auxiliary relay X^3 remains closed because its holding circuit is completed through contact 66 operated by signal S^3 . Then after relay R^3 is closed, the holding circuit

for relay X^3 is completed through the front point of contact 55 of relay R^3 and polar contact 86 of relay R^3 , so relay X^3 remains closed. Relay R' therefore continues to be energized from battery P^3 , and pole-changer G^3 is in such position that signal S' moves to clear position. As the train passes from sub-section C—H into sub-section H—A it causes no change in the circuits or signals for stretch A—B. As it leaves the stretch it opens track relay T^7 to the west of stretch A—B, thereby opening relay R^7 so signal S^7 changes to danger. The closing of track relay T^2 energizes relays R^2 and R^5 so that signals S^2 and S^5 change to clear position. This movement of signal S^5 reverses pole-changer G^5 thereby reversing relay R^3 so that signal S^3 moves to clear; auxiliary relay X^3 then opens, thereby transferring relay R' to battery M^2 . It will be noted that signal S^5 changed to clear position immediately after the train left the stretch A—B, because relay R^5 then became energized from battery M^2 independently of pole-changer G^7 . The only time signal S^5 indicates caution is when the track section immediately to the west of section A—H is occupied and a westbound train is approaching this signal. Relay R^2 is then open and pole-changer G^7 is reversed, so that battery M^2 is connected with relay R^5 in the proper direction to cause signal S^5 to indicate caution.

The operation of the apparatus during the passage of an eastbound train through the stretch is similar to that just explained, except as follows: As the train leaves the stretch it changes signal S^7 next to the east to danger, thereby closing the corresponding relay X^7 , and thus removing signal relay R^8 from the control of the first track relay for such sub-section to the east. Signal S^8 then changes to caution and signal S^6 to clear as soon as track relay T^7 closes, thereby avoiding any unnecessary delay to traffic. It will be seen therefore that when a train is moving west, track relay T^2 controls signal S^8 next to the west, but that this control is removed while a train is moving east.

Although I have herein shown and described only a few forms of signal systems embodying my invention, it is understood that various changes and modifications may be made therein within the scope of the appended claims without departing from the spirit and scope of my invention.

Having thus described my invention, what I claim is:

1. In combination, a stretch of railway track, signals located at intervals through said stretch for governing traffic in one direction, and other signals located at intervals for governing traffic in the other direction, a signal relay for each signal for

- the control thereof, a signal relay circuit extending through the stretch and including in multiple the relays for the signals governing traffic in one direction, and another signal relay circuit extending through the stretch and including in multiple the relays for the signals governing traffic in the other direction, main sources of current one included in each of said circuits and located adjacent the end at which traffic governed by the corresponding signals leaves the stretch, track circuits for the stretch including track relays for controlling said signal relay circuits, auxiliary sources of current located at intervals through the stretch, and means for each signal for opening at that point the corresponding signal relay circuit and connecting an adjacent auxiliary source with the portion of such circuit extending to the rear from said point. 5
2. In combination, a stretch of railway track divided into a plurality of successive sections, a pair of opposing signals located adjacent each junction of two sections, a signal relay for each signal for the control thereof, a signal relay circuit extending through the stretch and including in multiple the relays for the signals governing traffic in one direction, and another signal relay circuit extending through the stretch and including in multiple the relays for the signals governing traffic in the other direction, main sources of current one included in each of said circuits, and located adjacent the end at which traffic governed by the corresponding signals leaves the stretch, track circuits for the stretch including track relays for controlling said signal relay circuits, auxiliary sources of current located adjacent the signals, an auxiliary relay for each signal for opening at that point the corresponding signal relay circuit and connecting an adjacent auxiliary source with the portion of the circuit extending to the rear from such point, contacts operated by each signal, a pick-up circuit for each auxiliary relay including a contact operated by the corresponding signal and closed when the signal indicates clear and a contact operated by the adjacent opposing signal and closed when the signal indicates danger, and a holding circuit for each auxiliary relay including a contact of the auxiliary relay itself and a back contact of the signal relay for the corresponding signal. 10
3. In combination, a stretch of railway track divided into a plurality of successive sections, a pair of opposing signals located adjacent each junction of two sections, a signal relay for each signal for the control thereof, a signal relay circuit extending through the stretch and including in multiple the relays for the signals governing traffic in one direction, and another signal relay circuit extending through the stretch and including in multiple the relays for the signals governing traffic in the other direction, main sources of current one included in each of said circuits, and located adjacent the end at which traffic governed by the corresponding signals leaves the stretch, track circuits for the stretch including track relays for controlling said signal relay circuits, auxiliary sources of current located at intervals through the stretch, and means for each signal for opening at that point the corresponding signal relay circuit and connecting an auxiliary source with the portion of the circuit extending to the rear from said point. 15
4. In combination, a stretch of railway track, signals located at intervals for governing traffic in one direction through said stretch, a signal relay for each signal for the control thereof, a signal relay circuit extending through the stretch and including said relays in multiple, said circuit also including a main source of current adjacent the end at which traffic in the said direction leaves the stretch, track circuits for the stretch including track relays for controlling said signal relay circuit, auxiliary sources of current located at intervals through the stretch, and means for each signal for opening the said signal relay circuit at that point and connecting an auxiliary source with the portion of the circuit extending to the rear from said point. 20
5. In combination, a stretch of railway track, signals located at intervals for governing traffic through the stretch in one direction, a signal relay for each signal for the control thereof, two line wires extending through said stretch, the said signal relays being connected in multiple across said wires, a source of current connected across said wires adjacent the end of the stretch at which a train moving in the said direction leaves the stretch, track circuits for the stretch including track relays for controlling one of said line wires, auxiliary sources of current located at intervals in said stretch, and means for each signal for opening one of the said line wires at that point and connecting an auxiliary source with the portion of the line wire extending to the rear from said point and with the other line wire. 25
6. In combination, a stretch of railway track, signals located at intervals for governing traffic in one direction through said stretch, a signal relay for each signal for the control thereof, said relays being connected in multiple, a main source of current for said multiple circuit, track circuits for 30

the stretch including track relays for controlling said signal relays, each track relay when affected by the presence of a train operating to disconnect from said source the 5 signal relay for the signal which immediately governs the corresponding section of track and all of the signal relays for the signals in the rear, auxiliary sources of current and auxiliary relays one for each signal for 10 connecting an auxiliary source with the signal relays for the signals in the rear of such signal.

7. In combination, a stretch of railway track divided into a plurality of sections, 15 signals for governing traffic in one direction through the stretch, a signal being located adjacent the entrance end of each section, a signal relay for each signal for the control thereof, said relays being connected in multiple, a main source of current for said multiple circuit, track circuits for the sections including track relays for controlling said signal relays, each track relay when affected by the presence of a train operating to 20 disconnect from said source the signal relay for the signal for the corresponding section and the signal relay for each signal in the rear, auxiliary sources of current, and auxiliary relays one for each signal for connecting an auxiliary source with the signal 25 relays for the signals in the rear of such signal.

8. In combination, a stretch of railway track, signals located at intervals for governing traffic in one direction through said 30 stretch, each signal being adapted to indicate danger, caution and clear, a three-position relay for each signal for the control there-

of, said relays being connected in multiple, a main source of current for said multiple circuit, track circuits for the stretch including track relays for controlling said signal relays, auxiliary sources of current, auxiliary relays one for each signal for disconnecting the signal relays for the signals in the rear of said signal from the main source and connecting them with an auxiliary source, and a pole-changer operated by each signal for reversibly connecting the signal relay for the signal next in the rear with the auxiliary source which energizes such relay. 40 45 50

9. In combination, a stretch of railway track, signals located at intervals for governing traffic in one direction through said stretch, a signal relay for each signal for the control thereof, a signal relay circuit extending through the stretch and including said relays in multiple, said circuit also including a main source of current adjacent the end at which traffic in the said direction leaves the stretch, track circuits for the stretch including track relays for controlling said signal relay circuit, auxiliary sources of current located at intervals through the stretch, and means for each 60 65 branch of said circuit for opening the circuit in such branch and connecting an auxiliary source with the portion of the circuit extending to the rear.

In testimony whereof I affix my signature 70 in presence of two witnesses.
